DESIGN FOR A CORNER SECRETARY OR THE LIKE

Mack E. Garner, Newport News, Va.

Application March 19, 1940, Serial No. 91,075

Term of patent 7 years

To all whom it may concern:

Be it known that I, Mack E. Garner, a citizen of the United States, residing at Newport News, in the county of Warwick and State of Virginia, have invented a new, original, and ornamental Design for a Corner Secretary or the Like, of which the following is a specification, reference being had to the accompanying drawings, forming part thereof.

I claim:

The ornamental design for a corner secretary or the like, as shown.

MACK E. GARNER.
